UNITED STATES PATENT OFFICE

2,176,145

CASH REGISTER

Gunner Nelson, Dayton, Ohio, assignor to The National Cash Register Company, Dayton, Ohio, a corporation of Maryland

Application March 10, 1934, Serial No. 714,955

13 Claims. (CL 235--4)

This invention relates to cash registers and the like, but more particularly to the adaptation of a card perforating device to a register of the type illustrated and described in Letters Patent of the United States No. 1,761,542, issued June 30, 1930 to E. M. Shipley, and Patents Nos. 1,817,883 and 1,865,147, issued respectively August 4, 1931 and June 28, 1932, to E. M. Shipley.

Broadly speaking, the main object of this invention is to adapt a card perforating device for use on the type of cash registers disclosed in the patents referred to above.

Another object is to provide means to disable the card feeding mechanism during the preliminary cycle of machine operation.

Another object is to devise means to disable the mechanism that presents record cards to the feeding means during the first cycle of a two cycle machine operation.

Still another object is to provide means to re-enable the presenting means during the second cycle of a two cycle machine operation.

Another object is to contrive means to record the kind of operation being performed.

A further object is to supply means to make a record of total taking operations, this record also revealing in which totalizer line the transaction took place.

With these and incidental objects in view, the invention consists of certain novel features of construction and combinations of parts, the essential elements of which are set forth in appended claims and a preferred form of embodiment of which is hereinafter described with reference to the drawings which accompany and form part of this specification.

Of said drawings:

Fig. 1 is a side elevation as observed from the righthand side of the machine, depicting the cycle control mechanism.

Fig. 2 is a sectional view taken through the machine just to the right of an amount bank showing in particular an amount bank and its associated differential mechanism.

Fig. 3 is a side elevation of the total control lever showing in detail the mechanism for selecting the record perforating punches for said total control lever.

Fig. 4 is a sectional view taken just to the right of the perforating mechanism, picturing the mechanism for feeding the record card to the perforating mechanism and the mechanism for controlling the feeding mechanism during total taking operations.

Fig. 5 is a detail view of the train of gears for

driving the record card feeding and ejecting mechanism.

Fig. 6 is a sectional view of the perforating mechanism showing in particular the mechanism for operating and controlling said perforating mechanism.

Fig. 7 is a detail view showing the method of mounting the perforating punches.

Fig. 8 is a view as observed from the front of the machine showing the perforating mechanism together with its selecting and controlling mechanism.

Fig. 9 is a top plan view of the mechanism for selectively controlling the perforating mechanism.

Fig. 10 is a facsimile of a record card used in the machine of the instant invention and illustrates a record made during a typical adding operation.

Fig. 11 is another facsimile of a ledger card used in the machine of this invention and illustrates a record made during a typical total-taking operation.

GENERAL DESCRIPTION

Speaking in general terms the instant invention consists of a perforating device which is incorporated in a standard type of cash register and which in no way interferes with the regular functioning of said cash register.

A reservoir or supply compartment is provided for the reception of a plurality of a standard type of ledger or record cards and in each machine operation one of said cards is automatically conveyed from the reservoir to the feeding rolls and then to the perforating mechanism where the various data set up on the machine keyboard is punched in the proper columns on said data card. After this the card is conveyed by the feeding rolls to ejector rolls which in turn deposit the card in a suitable receptacle.

In adding and subtracting operations the machine operates through one cycle of movement, and in total taking operations it operates through two cycles of movement. In order to prevent two cards being fed through the perforating mechanism in total taking operations, mechanism has been devised to disable the mechanism that conveys the card from the reservoir to the feeding rolls during the first cycle of said total taking operation.

The record cards have a plurality of vertical columns designated by the proper titles, such as Amount, Ledger number, Date, etc. Each col-

15

50

55

umn has one or more rows of figures representing the numerical value and the position of the perforating punches. There is also a column on the ledger card for recording the type of operation (adding, reading or resetting) performed by the machine. The mechanism for recording the type of operation is controlled by the shifting of the total control lever which selects a perforating punch representative of the type of operation being performed, and in totalizing operations the punch selected is also representative of the particular totalizer in which the computation is taking place.

The punches for perforating the data set up on the keyboard of the machine are selected by projections formed on reciprocating racks, which racks are controlled in their movement, along with the usual printing wheels (not shown), by the differential mechanism of the machine.

After the card is fed into the perforating mechanism the entire perforating assembly is moved upwardly, the perforating punches being moved upwardly by contacting the record card. The punches over which the projections on the racks have been positioned are stopped in their upward movement by said projections and thereby forced through the card, which is backed up by a die plate having a plurality of holes in alignment with and arranged to receive the lower ends of the perforating punches. Downward movement of the perforating assembly strips the punches from the card and said card is then automatically deposited in the receiving well.

The instant invention provides the numerous advantages of a perforating mechanism in a machine of moderate cost and furnishes a means whereby a merchant may, over a period of time accurately check the amount and number of sales made by individual clerks, the number and size of articles sold, the department in which the transaction took place, and the type of transaction, for example, Cash sale, Charge sale, Received-on-account, Balances, etc.

These ledger or record cards may be analyzed at any time desired without danger of the mistakes incidental to hand-posting by running said cards through a standard card controlled tabulating machine.

The mechanism pertinent to the instant invention will now be described in detail.

DETAILED DESCRIPTION

The instant invention is embodied in the type of cash register illustrated and described in the patents referred to at the beginning of this specification. As machines of this character are well known in the art the mechanism thereof having no direct bearing on the instant invention, will be but briefly described.

Machine frame work and operating mechanism

Calling attention to Figs. 1 and 2, the mechanism of the machine proper is supported by main frames 30 and 31 and various other intermediate frames, cross-frames and braces. The main frames 30 and 31 are in turn secured to a machine base 32. The machine proper is enclosed in a suitable cabinet 28 (Fig. 1) secured to the machine base 32, while the perforating mechanism is enclosed in a case 29 (Fig. 6) which also surrounds the drawer mechanism and forms a pedestal for the machine proper.

The machine is operated by the usual electric motor (not shown) which is operatively con-

nected to a main drive shaft 33 by a clutch mechanism, (also not shown).

Depressing the usual starting bar releases a key lock shaft 34 (Fig. 1) for a slight clockwise movement under influence of a spring 35. This movement of the shaft 34 engages the clutch mechanism and closes the electrical circuit to the motor, thereby causing the machine to operate. Near the end of machine operation the shaft 34 is rocked counterclockwise by mechanism later to be described, to release the depressed keys and to disengage the clutch mechanism and simultaneously break the electrical circuit to the motor by opening the motor switch.

The machine may also be operated by means of a hand crank 36 (Fig. 1) which is connected to a pinion 37 journaled on a hub secured in the right machine frame 30. The pinion 37 meshes with a gear 38 turnably mounted on a stud 40 secured in the right frame 30. The gear 38 meshes with a gear 41 secured to the main drive shaft 33. Depressing the starting bar releases the shaft 33 for rotation. The machine may then be operated by means of the hand crank 36 and its associated mechanism.

As the operating and releasing mechanisms used in the machine of this invention are of conventional design they have not been illustrated herein and it is therefore thought unnecessary to further describe these mechanisms. However, reference may be had to the Shipley Patent No. 1,761,542 issued June 3, 1930 for a full disclosure of this mechanism.

Cycle controlling mechanism

In adding operations it is necessary for the shaft 33 (Fig. 1) to make one complete clockwise revolution and in total taking operations it is necessary for this shaft to make two complete clockwise revolutions. The mechanism that controls the cycle of operation of this shaft is well shown in Figs. 1 and 3 and will now be described.

Secured on the righthand end of the key lock shaft 34 is an arm 42 carrying a stud 43 which extends through a slot in a link 44, the lower end of which is bifurcated to embrace a stud 45 in a pitman 46 having a slot which embraces the stud 40. The lower end of the pitman 46 is pivotally connected to an arm 47 loosely mounted on a stud 48 secured in the frame 30. A forward extension of the arm 47 is pivotally connected by a link 49 to an arm 50 secured on the right-hand end of a zero stop lever throw-out shaft 51 journaled in the frames 30 and 31.

The link 44 has a stepped opening 52 which cooperates with a stud 53 in an arm 54 loose on the stud 48. The arm 54 carries a roller 55 which cooperates with a raceway 56 in the gear 38. The raceway 56 has diametrically opposed camming irregularities which cooperate with the roller 55 near the end of each cycle of movement to rock the arm 54 first clockwise and then back to normal position. In Fig. 1 the cycle controlling mechanism is shown in adding or normal position. Releasing the machine for an adding operation by depressing the starting bar releases the shaft 34 to the action of the spring 35 which rocks said shaft clockwise until the projection on the arm 42 engages a stop stud 57 secured in the right frame 30. This as previously explained engages the motor clutch and closes the motor switch.

It will be recalled that in adding operations

the shaft 33 makes one complete revolution clockwise, which by means of the gear 41 rotates the gear 38 one-half revolution counterclockwise. When the gear 38 has been rotated nearly one-half revolution one of the diametrically opposed irregularities in the cam race 56 rocks the arm 54 first clockwise. This movement of the arm 54 due to the fact that the stud 53 engages the upper step in the opening 52 on the link 44 imparts full downward movement to said link 44 to restore the key lock shaft 34 counterclockwise which disengages the motor clutch and opens the motor switch. The arm 54 is then returned counterclockwise to the position here shown. Counterclockwise restoring movement of the shaft 34 also releases all the depressed keys and likewise restores the starting bar to normal position.

In total taking operations it is necessary that the main drive shaft 33 make two complete clockwise revolutions and the gear 38 one complete counterclockwise revolution. This is accomplished in the following manner:

In Fig. 3 a total control lever 58 is shown in adding position. Shifting the total control lever 58 in either direction away from adding position causes a slot 59 therein in cooperation with a stud in an arm 60 to rock said arm 60 a slight distance counterclockwise on its pivot 61. The arm 60 by means of a slot 62 formed by the edge of arm 60 and the edge of an arm 63, in cooperation with a stud 64 in an arm 64 secured on the zero stop lever throwout shaft 51, rocks said arm and shaft a slight distance clockwise (see also Fig. 1). This slight clockwise movement of the shaft 51 by means of the arm 60, the link 49 and the arm 47 imparts a slight forward movement to the pitman 46, which by means of the stud 45 shifts the link 48 clockwise to disengage the stud 53 from the upper step in the opening 52 and to align the intermediate step in said opening 52 with said stud 53.

The pitman 46 carries a roller 66 which normally engages a notch in a raceway 67 of the cam 39 to hold said cam stationary during adding operations. The forward movement of the pitman 46, caused by moving the total control lever away from adding position disengages the roller 66 from the notch and moves it into the raceway 67 of the cam 39. Forward movement 50 of the pitman 46 also couples the cam 39 to the gear 38 in the well known manner.

When the machine is released for operation the gear 38 and the cam 39 revolve counterclockwise in unison, the raceway 67 cooperating with the stud 66 in the pitman 46 gives added forward movement to the pitman 46 to move the link 44 so that the longest portion of the opening 52 is in alignment with the stud 53. Consequently when the first irregular portion of the raceway 56 in the gear 38 rocks the arm 54 as explained above, the stud 53 moves idly in the opening 52 without restoring the key lock shaft 34 thereby allowing the machine to operate through another cycle of movement.

Near the end of the second cycle of movement the cam 39 returns the pitman 46 and the link 44 to a position where the intermediate step 65 of the opening 52 is aligned with the stud 53 in the arm 54. Movement of the arm 54 as explained above causes the stud 53 to engage the step 65 to rock the arm 42 and the shaft 34 a sufficient distance counterclockwise to disengage the motor clutch mechanism, restore the starting bar and release the depressed transaction keys.

It will be noted that the key lock shaft 34 re-

ceives less counterclockwise restoring movement in total taking operations than in adding operations. The additional movement for adding operations is necessary in order to release the depressed amount keys.

The foregoing description of the cycle controlling mechanism is deemed sufficient for the purpose of this invention. However, if a further description of this mechanism is desired reference may be had to the patents referred to hereinbefore.

Amount keys and differential mechanism

The machine of this invention has a plurality of banks 68 (Fig. 2) of amount keys 69 and as 15 the machine illustrated is arranged for English currency the two lower denominational amount banks have eleven keys and all the other amount banks have nine keys. As all the amount banks and their associated differential mechanisms are 20 similar it is thought that the description of one such unit will be sufficient.

Calling attention to Fig. 2, the amount banks 68 are removably supported on rods 70 and 71 extending between and supported by the frames 25 30 and 31. Pivot on the lower end of each amount bank is a zero stop lever 72 having a right angled projection arranged to cooperate with the forward end of a reset spider 73 pivoted on a hub 74 of an amount differential actuator 75 loosely mounted on a hub 76 extending between two differential support plates 77 carried by a pair of rods 78 extending between the frames 30 and 31. The spider 73 has in its forward end a slot through which extends a stud 35 79 in a differential latch arm 80 pivoted to the actuator 75.

Mounted for parallel shifting movement by means of the arm 80 and a similar arm 81 is a differential latch 82, a foot shaped projection of 40 which is arranged to cooperate with a depression in a driving segment 83 pivoted on the hub 76 and connected by a link 84 to a cam lever 85 journaled on a stud 86 secured in one of the plates 77. The lever 85 carries a pair of rollers 86 which cooperate with the periphery of companion cams 87 and 88 secured on the main drive shaft 33.

In adding operations the shaft 33 makes one complete revolution clockwise, which by means of the lever 85 and the link 84 rocks the driving 50 segment 83 first in a clockwise direction and then back to normal position.

As previously stated there is a differential actuator unit like that explained above for each amount bank and each differential unit is supported between two of the plates 77. The complete assembly of differential units are held together by means of a rod 89 extending through the hubs 76.

If no key is depressed in an amount bank the 60 zero stop lever 72 engages the forward end of the reset spider 73 to rock the latch arm 80 counterclockwise to move the differential latch 82 forwardly thereby disengaging the foot of said latch from the depression in the driving segment 83 and engaging a nose 90 of said latch with one of 65 a series of notches 91 in a plate 92 secured to the plate 77. This stops the differential actuator 75 in zero position by disengaging said latch from 70 the driving segment 83.

A concentric portion of the segment 83 in cooperation with the latch 82 maintains the nose of said latch in engagement with the plate 92 while said segment completes its initial movement 75

clockwise and during the greater part of the return movement of said segment until the depression therein is opposite the foot of the latch 82. When the depression is opposite the foot of the latch 82 a flat surface of the segment 83 engages a stud 93 in the actuator 75 and returns said actuator to its home position thereby disengaging the reset spider 73 from the zero stop lever 72 and allowing a spring 94 to disengage the nose 90 of the latch 82 from the notch in the plate 92 and to reengage the foot of said latch with the depression in the driving segment 83.

Depressing one of the keys 69 in an amount bank forces the lower end of the stem thereof into the path of the latch arm 80. Consequently initial movement clockwise of the segment 83 and the actuator 75 causes said arm 80 to engage the stem of said key to disengage the foot of the latch 82 from the segment 83 in exactly the same manner as explained above. In its return movement the segment 83 engages the stud 93 to return the actuator 75 and disengage the latch 82, as explained above.

It is probably well to state here that depression of an amount key rocks the zero stop lever 72 counterclockwise out of the path of the spider 73 thereby allowing the actuator unit to travel clockwise until stopped by the depressed amount key.

30 Totalizers and transaction keys

The machine of this invention has three lines of interspersed totalizers, a front line 95, (Fig. 2) a rear line 96, and an upper line 97. Each totalizer line has a plurality of sets of totalizer wheels 98, the teeth of which cooperate respectively with three sets of teeth on the differential actuators 75.

In adding operations the different totalizers on a line are selected and aligned with the actuators under control of the transaction keys, there being a bank of transaction keys for each totalizer line. In total taking operations the desired totalizer line is selected for engagement with the actuators by positioning the total control lever and the different sets of totalizer wheels on the selected line are selected and aligned with the actuators under control of the transaction keys as in adding operations.

In adding operations the wheels of the selected 50 totalizer are engaged with the actuators 75 immediately after the actuators have been positioned by the depressed amount keys. Return movement of the actuators revolves the totalizer wheels commensurate with the value of the depressed amount keys.

In the first cycle of a total taking operation the zero stop levers 72 (Fig. 2) break or stop all the amount differential latches in zero position. This is to allow time for the selected set of totalizer wheels to be aligned with the actuators. At the beginning of the second cycle of a total taking operation the selected totalizer is engaged with the actuators 75 and the zero stop levers 72 are rocked out of the path of the spiders 73. Clockwise movement of the actuators 75 revolves the wheels of the engaged totalizer in a reverse direction until they are stopped in zero positions by means of a long tooth on each wheel. This 70 positions the actuators commensurate with the amount on the totalizer wheels and return movement counterclockwise of the actuators in turn positions the recording and indicating mechanisms in accordance with the amount on said totalizer wheels.

Recorder and indicator positioning mechanisms

The manner in which the punch selecting, printing and the indicating mechanisms are positioned by means of the actuator 75 will now be described:

Again directing attention to Fig. 2, pivoted on the actuator 75 is a beam 99 bifurcated to embrace a stud 100 in a link 101, the upper end of which is pivoted to an indicator segment 102 loose on an indicator tube line 103. The lower end of the link 101 is pivoted to an arm 104 loose on a tube line 106 and connected by one of the tubes 105 to a segment 107. The segment 107 has two sets of teeth, the upper set of which is adapted to position the printer wheels, and a lower set 108 15 which is adapted to mesh with teeth in a perforator selecting rack 109 (Fig. 6) to position said rack commensurate with the position of the actuator 75 in a manner later to be described.

Immediately after the actuator 75 has been 20 positioned by the depressed amount key or by the long tooth of the totalizer wheel 98, as explained above, and before said actuator starts its return movement counterclockwise a roller 110 on the cam lever 85 engages an arcuate surface 111 of 25 the beam 99 and forces said beam upwardly until an annular surface 112 thereof engages the periphery of the hub 74. This causes the beam 99 by means of the link 101 to position the indicator segment 102 and the segment 107 in accordance 30 with the position of the actuator 75. Return movement counterclockwise of the actuator 75 removes the annular surface 112 from engagement with the hub 74 but does not disturb the position of the link 101, the indicator segment 35 102 or the segment 107. Consequently the indicators, punch selectors, and the printing wheels remain positioned at the end of machine operation.

A liner 113 (Fig. 2) cooperates with the teeth 40 of the segment 102 to align said segment in set position. At the beginning of the machine operation the liner 113 is disengaged from the teeth of the segment 102 and is reengaged therewith immediately after the segment has been positioned 45 as described above.

The usual transfer mechanism is employed for transferring amounts from lower to higher denominations.

50 Card perforating mechanism

The machine illustrated is provided with mechanism to perforate amounts and other data on record cards, said amounts and data corresponding to the keys depressed and said machine is 55 also arranged to perforate the results of total taking operations on said record cards. In a total taking operation a record is also perforated of the totalizer in which the transaction took place and whether the totalizer was read or reset. 60

In order to prevent two cards being fed through the perforating mechanism during total taking operations, mechanism has been devised to disable the card feeding mechanism during the first cycle of a totalizing operation. Movement 65 of the total control lever away from adding position renders this disabling mechanism effective. In the following explanation the perforating mechanism will be treated in detail.

70 Support of perforating mechanism

The perforating mechanism is supported by two side frames 114 and 115 (Figs. 6 and 8) connected by cross bars 116, 117 and 118 and a plate 119. The perforating mechanism assembly rests 75

on a cabinet base 120 and is connected to the machine proper by two bolts 121, secured in the bars 116 and 117 and extending through a cabinet top 122 and the machine base 32.

5 **Rack mechanism**

It will be recalled that the machine used to illustrate the instant invention is arranged for English currency. Consequently the two lowest denominations have twelve divisions. Fig. 6 is an offset sectional view taken just to the right of the second denomination or pence segment 107 and just to the right of the corresponding row of perforating punches 123. The amount racks 109 (Figs. 6, 8 and 9) are supported between the plates 114 and 115 for horizontal reciprocating movement by means of slots in said racks which embrace a rod 124 extending between said plates 114 and 115 and by means of a cross bar 125 extending between the plates 114 and 115 having therein a plurality of slots adapted to receive the forward ends of the amount racks 109.

20 The differential movement of the amount racks 109 is transferred to auxiliary punch selector racks 126 in the following manner:

25 The rack 109 has thereon a plurality of teeth which cooperate with a pinion 127 secured on a pinion shaft 128, opposite ends of which are journaled in the plates 114 and 115. Another pinion 127, secured on the shaft 128 (Fig. 9) meshes with teeth on the auxiliary rack 126. Consequently any differential movement imparted to the rack 109 is transmitted to the rack 126 by the pinion shaft 128.

30 It should be borne in mind that what applies to this one denominational unit applies to all the other denominational units and the row of transaction keys and the clerks' keys as well.

35 The rack 126 (Fig. 6) has a downwardly extending projection 129 adapted to cooperate with the perforator punches 123 in a manner later to be described. The perforating punches 123 fit loosely in openings in an upper guide plate 130, an intermediate guide plate 131 and a lower guide plate 132. The intermediate plate 131 and the lower plate 132 are secured in fixed relation to a die plate 133 having therein a plurality of openings corresponding to the punches 123 and adapted to receive the lower ends of said punches. The plates 131, 132 and 133 (Figs. 6 and 8) are secured to a vertically slidable frame 134 composed of two side rails 135 connected by end plates 136 and 137. The end plates 136 and 137 have secured thereto blocks 138 adapted to slide vertically in slots in plates 139 secured respectively to the frames 114 and 115. The plate 130 is fixedly supported by the plates 139.

40 Calling attention to Figs. 6 and 7, the punches 123 are retained in position in the plates 130 and 131 by means of wires 140 which fit loosely in relieved portions of adjacent punches 123, (note particularly Fig. 7). There are two wires 140 for each two rows of punches, said wires being retained in place on the top surfaces of the plates 130 and 131 by means of clamps 141 and 142 secured respectively to the plate 130 and bars 143 which space the plates 131 and 132. The wires 140 secured to the stationary plate 130 disengage the punches from the perforated card and determine the home position of said punches, and the wires secured to the movable plate 131 return the perforating punches to home positions. The wires 140 provide a means for conveniently removing any single punch or as many punches as desired from the perforating assembly with a

minimum amount of effort and without removing the perforating assembly from the machine.

45 The plates 132 and 133 are spaced a slight distance apart to receive one of the record cards shown in Figs. 10 and 11, which is fed therebetween by means of mechanism later to be described, and which is positioned in relation to the perforating punches 123 by mechanism also to be described later. After this the perforating die assembly is moved upwardly by mechanism 10 now to be described to perforate the record card commensurate with the depressed amount keys in adding operations, and in total taking operations the card is perforated in accordance with the amount standing on the totalizer read or reset. 15 After the card has been perforated the die frame 134 (Fig. 6) is returned downwardly to its normal position as here shown.

20 The mechanism for accomplishing the above result will now be described.

25 The end plates 136 and 137 (Figs. 6 and 8) each carry a roller 144 embraced by the bifurcated ends of arms 145 and 146 secured on a shaft 147 journaled in the frames 114 and 115. The arm 145 has a Y-shaped rearward extension carrying 25 a pair of rollers 148 which cooperate with companion cams 149 and 150 secured on an operating shaft 151 opposite ends of which are journaled in the frames 114 and 115.

30 By referring to Fig. 4 it will be seen that the shaft 151 has secured thereon a gear 152 operatively connected by intermediate gears 153 and 154 to a driving gear 155 secured on the main drive shaft 33. The intermediate gear 153 is secured on a shaft 156 turnably mounted in the 35 frames 114 and 115 and the intermediate gear 154 is secured on a short shaft 157 journaled in a bushing supported by the frame 114.

35 As the intermediate gears 153 and 154 are the same size, that is, have the same number of 40 teeth, and the gears 152 and 155 also have an equal number of teeth, movement of the shafts 33 and 151 is synchronized and when the shaft 33 makes one complete clockwise revolution the shaft 151 is given one complete revolution in a counter- 45 clockwise direction. This counterclockwise revolution of the shaft 151 (Fig. 6) by means of the companion cams 149 and 150 in cooperation with the arm 145 oscillates the shaft 147 first clockwise and then back to normal position to move 50 the perforating die frame 134 first upwardly to perforate the record card inserted between the plates 132 and 133 in a manner presently to be described, after which said frame is returned downwardly to normal position as here shown. 55

Differential positioning of the punch selecting rack

60 Directing attention to Fig. 2, the arm 104 and the segment 107 are differentially positioned by 60 means of the link 101 in cooperation with the beam 99 in the manner explained earlier herein. This differential positioning of the segment 107 (Figs. 6 and 9) is transmitted to the rack 109 by means of the teeth 108 in cooperation with teeth 65 on said rack 109. The differential positioning of the rack 109 is then transmitted to the auxiliary rack 126 by means of the pinion 127 and the pinion shaft 128. This positioning of the auxiliary rack 126 places the projection 129 directly 70 over the perforating punch 123 corresponding to the depressed amount key in adding operations or corresponding to the amount on the totalizer wheel being read or reset in total taking operations.

As the perforating frame 134, which includes the plates 131, 132 and 133 is moved upwardly the record card, which as previously stated, has been inserted between the plates 132 and 133, is moved into contact with the lower ends of the perforating punches 123 and carries said punches upwardly with the frame 134 until the upper end of the selected punch 123 is moved into contact with the projection 129 of the auxiliary rack 126. This blocks the movement of the perforating punch, and as the perforating frame 134 continues to travel upwardly said punch is forced through the record card to make a perforation therein commensurate with the depressed amount key or the position of the totalizer wheel as shown in section 295 of Figs. 10 and 11 respectively. Opposite the projection 129 on the rack 126 is a raised surface which cooperates with the lower surface of the plate 119 to back up the rack 126 during perforation.

What has been said about the amount perforating mechanism applies equally as well to the clerks' symbol perforating mechanism and the transaction perforating mechanism as the auxiliary punch selecting racks for the clerks' keys and the transaction keys are differentially positioned in exactly the same manner as the amount auxiliary rack 126. (See "Clerks" and "Transactions" columns of the record cards shown in Figs. 10 and 11.)

Total control lever perforating mechanism

Means under control of the total control lever is provided for recording what type of operation, add, read or reset, is being performed by the machine and in which totalizer line the reading or resetting operation is taking place. This mechanism is clearly shown in Figs. 3 and 9 and will now be described.

The total control lever 58 (Fig. 3), which is turnably supported by a stud 160 secured in the end plates of the total control assembly, is pivotally connected by a link 161 to an arm 162 secured on the shaft 105. Secured on the left-hand end of the shaft 105 is a segment 163 (see also Fig. 8), having teeth which mesh with similar teeth in a rack 164, slidably supported by the rod 124 and bar 125 in exactly the same manner as the amount rack 109. The rack 164 has in its bottom edge teeth which cooperate with the teeth of a pinion 165 (see also Fig. 9) connected by a sleeve 167 to a similar pinion 166. The pinions 165 and 166 and the sleeve 167 are rotatably supported on a pinion shaft 168 opposite ends of which are journaled in the frames 114 and 115. The pinion 166 meshes with the teeth of an auxiliary rack 169 slidably supported by the rod 124 and the bar 125 in exactly the same manner as the auxiliary amount racks 126. The auxiliary rack 169 has a downwardly extending projection 170 which cooperates with a series of perforating punches 171 (Fig. 3) which may be selected to make a record of the type of operation being performed. Punches 171 are supported by the plates 130, 131 and 132 in exactly the same manner as the amount perforating punches 123 (see Figs. 6 and 7).

By referring to Fig. 8 it will be seen that adjacent the punches 171 there is a row of auxiliary punches 172. The punches 172 are merely for the purpose of retaining the wire 140 (see Figs. 6 and 7) in position and have no bearing whatever or connection with the auxiliary rack 169. There is also an extra row of punches 173 in the amount and transaction groups and an extra

row of punches 174 in the date group of perforating punches. These two rows of punches are for the same purpose as the punches 172, that is, to retain the wires 140 in position.

In Fig. 3 the total control lever 58 is shown in adding position, in which position the link 161 by means of the arm 162, the shaft 105 and the segment 163 positions the rack 164 and the auxiliary rack 169 where the projection 170 is directly over the middle punch in the group of seven punches 171. Operation of the machine causes the selected perforating punch 171 to be forced through the record card, position 5, column 296, Fig. 10, to record the type of operation being performed. In addition to the adding position, the total control lever 58 has three positions above adding position for selecting the three totalizer lines for reading operations and three positions below adding position for selecting the three totalizer lines for resetting operations.

Moving the total control lever 58 clockwise to select one of the totalizer lines for a reading operation by means of the link 161 rocks the arm 162, the shaft 105 and the segment 163 counter clockwise to move the racks 164 and 169 rearwardly to vertically align the projection 170 with the punch 171 corresponding to the position of the total control lever.

In a like manner, moving the total control lever 58 counterclockwise to one of its resetting positions moves the rack 169 forwardly so that the projection 170 is positioned opposite the upper end of the punch 171 corresponding to the reset position of said total control lever 58. Operation of the machine then causes the selected punch to be forced through the record card, position 6 column 296 Fig. 11, to record the type of operation, in this case reset, and the totalizer line in which the transaction took place. A shoulder 176 of the rack 169 (Fig. 3) cooperates with the lower surface of the plate 117 to assist said rack 169 in receiving the thrust imparted thereto when the punch 171 is forced through the record card.

Ledger number and date perforating mechanism

Means are also provided for perforating a record of the ledger or card number and the date in the respective columns on the record card. The ledger number and the date are set up by means of settable racks which may be manually positioned to the desired number or date. This mechanism is pictured in Figs. 6, 8 and 9, and will now be described.

Slidably mounted by means of the rod 124 and the bar 125 is a month rack 177 and two day racks 178 having upwardly extending finger pieces 179 which protrude through graduated apertures in a cover plate 158. The racks 177 and 178 have teeth which mesh with three identical pinions 180 connected by hubs 181 to pinions 182 which cooperate with an auxiliary month rack 183 and two day racks 184. The hub and pinion assembly for the month rack 177 is loosely supported by the shaft 168 and the hub and pinion assembly for the units of days rack 178 is revolvably supported by the shaft 128 while the pinion assembly for the tens of days rack 178 is turnably mounted on a shaft 185 opposite ends of which are journaled in the plates 114 and 115.

The auxiliary date racks 183 and 184 have downwardly extending projections 186 which cooperate with a series of date perforating punches 187 (Fig. 8) in exactly the same manner as explained for the amount perforating mechanism.

Extending between the frames 114 and 115 (Fig. 75

6) is a rod 194 loosely supporting a series of retaining pawls 195 having rounded noses 196 which are retained in engagement with a series of notches in the racks 177 and 178 by springs 197. 5 The pawls 195 cooperating with the notches in the racks 177 and 178 retain said racks in set positions.

Located on the lefthand side of the perforating unit is a plurality of manually settable racks 190 10 which are operatively connected to a series of auxiliary ledger number racks 191 by means of pinion and shaft assemblies in a similar manner to the date racks just explained. The ledger number racks 190 are retained in positions in exactly the same manner as the date racks 177 15 and 178. The auxiliary ledger number racks 191 have projections 192 which cooperate with the upper ends of ledger number perforating punches 193 in the same manner as described for the amount group of perforating punches.

Moving the date racks 177 and 178 (Figs. 6, 8 20 and 9) and the ledger number rack 190 to the desired date and ledger number, positions the auxiliary racks 183, 184 and 191 correspondingly. 25 This positions the downwardly extending projections 186 and 192 of the auxiliary date and ledger number rack over the proper perforating punches to record the date and ledger number in their respective columns on the record card (Figs. 10 30 and 11).

Record card feeding mechanism

Blank cards 159 to be run through the perforating mechanism are stored in a reservoir or supply compartment 198 (Figs. 4 and 9) composed of a box-like structure supported between the frames 114 and 115. A weight 199 is placed on top the stack of cards 159 to retain them in the reservoir and to maintain the bottom card in contact with the card picker mechanism that removes said bottom card from the reservoir and presents it to the feeding rolls. A block 200 secured to a plate 201 supported by the frames 114 and 115 cooperates with the lower edge of an adjustable blade 202 to form a variable aperture which may be adjusted to allow only one card at a time to pass to the feeding rolls.

Reciprocably mounted on the plate 201 is a cardpicker slide 203 having secured thereto a bracket 204 a downward projection of which extends through a slot in the plate 201. The bracket 204 carries a stud 205 embraced by the upper bifurcated end of an arm 206 secured on a shaft 207, opposite ends of which are journaled in the frames 114 and 115. Secured on the righthand end of the shaft 207 is an arm 208 to which is pivoted the forward end of a link 209 the rearward end of which is supported in a slot in a bracket 210 secured to the right perforator frame 114.

The rearward end of the link 209 has therein a T-shaped slot 211 which cooperates with a stud 212 in one arm of a yoke 213 loose on a stud 214 secured in the frame 114. The yoke 213 has another arm 215 carrying rollers 216 and 217 which cooperate respectively with the peripheries of companion plate cams 218 and 219 secured on the shaft 151. The link 209 is connected by another link 220 to a lever 221 (see also Fig. 1) 70 which fulcrums on a stud 222 secured in the frame 114. The upper end of the lever 221 is bifurcated to receive a stud 223 in a link 224 the rearward end of which is loosely connected to an arm 225 secured on a drawer release shaft 226 75 journaled in extensions of the machine base

32. The forward end of the link 224 is pivoted to one arm of a bell crank 227 secured on a shaft 228 opposite ends of which are journaled in the main frames 30 and 31. The bell crank 227 is connected by a link 229 to an arm 230 secured 5 to the zero stop lever throwout shaft 51.

Calling attention to Fig. 3, when in adding position, the total control lever 58, by means of the lever 60 and arm 64 positions the shaft 51, as here shown. This by means of the arm 230, link 10 229 (Figs. 1 and 4), bell crank 227, link 224, lever 221 and link 220 positions the link 209 as shown in Fig. 4, so that the upper portion of the T slot 211 engages the stud 212 carried by the yoke 213.

Releasing the machine for an adding operation, 15 in which it will be recalled the shaft 151 makes one complete counterclockwise revolution, causes the companion cams 218 and 219 in cooperation with the rollers 216 and 217 to rock the yoke 213 first counterclockwise and then back to normal 20 position. This by means of the link 209, arm 208, shaft 207 and arm 206 moves the slide 203 first in a rearwardly direction and then back to normal position as here shown.

Adjustably mounted on the forward edge of the 25 slide 203 is a bar 231 the top edge of which extends above the top surface of the cardpicker slide 203 a little less than the thickness of one of the record cards. The weight 199 maintains the bottom record card in contact with the top surface of the slide 203. Consequently when said slide makes its initial movement rearwardly the bar 231 engages and slides the bottom card 159 from beneath the stack and moves the forward edge thereof through the aperture formed by the 30 block 200 and the blade 202 and into engagement with a pair of feeding rolls 232 and 233.

It will be recalled that in total taking operations, both read and reset, it is necessary for the main drive shaft 33 to make two complete clockwise revolutions and consequently the shaft 151 is also revolved two complete counterclockwise revolutions. In order to prevent the slide 203 from receiving two excursions of movement in a total taking operation and consequently presenting two cards to the feeding means, it is necessary to disable the movement of said slide 203 during the first revolution of the shaft 151. This is accomplished in the following manner:

Shifting the total control lever 58 (Fig. 3) in 50 either direction away from adding position, by means of the slot 59 and the arm 60, rocks the arm 64 and the zero stop lever throwout shaft 51 a slight distance clockwise. This by means of the train of mechanism shown in Figs. 1, 3 and 4, 55 rocks the link 209 upwardly to align the horizontal portion of the T slot 211 with the stud 212. Consequently when the yoke 213 is oscillated back and forth during the first cycle of a total taking operation the stud 212 moves idly in the horizontal portion of the T slot 211.

During the second or last cycle of a total taking operation the mechanism shown in Fig. 1 gives added clockwise movement to the zero stop lever throwout shaft 51 as explained near the 65 beginning of this specification. This additional clockwise movement of the zero stop lever throwout shaft 51 rocks the link 209 (Fig. 4) upwardly to engage the lower portion of the T slot 211 with the stud 212. This operatively connects the yoke 70 213 to the link 209 and consequently during the last cycle of a total taking operation the slide 203 will be oscillated back and forth to present one of the record cards to the feeding means.

Secured in the link 209 (Fig. 4) is a stud 285 75

arranged to pass through notches 286 in the slot in the bracket 210 when the link 209 is in either of its effective positions in which it is operatively connected to the driving yoke 213. When the link 209 is in its intermediate or ineffective position the stud 285, due to the fact that it is not alined with either of the notches 286 blocks movement of the link 209 in case the stud 212 nibbles on either of the abrupt edges of the slot 211.

In addition to the feed rolls 232 and 233 there are two sets of feed rolls composed of pairs of rolls 234, 235, 236 and 237 and one set of ejector rolls 238 and 239 (Figs. 4 and 8). The pairs of feed rolls 234 and 236 are secured respectively on shafts 240 and 241 opposite ends of which are journaled in the frames 114 and 115. The pairs of rolls 235 and 237 are pivoted respectively on pairs of arms 242 and 243. The two pairs of arms 242 and 243 are in turn pivoted on upturned extensions of brackets 244 and 245 secured to the plate 132. The rollers 234, 235, 236 and 237 extend through suitable openings in the plates 132 and 133 and form contact with each other in the opening between said plates 132 and 133.

The feed rolls 232 and 233 are secured respectively to shafts 246 and 247 and the ejector rolls 238 and 239 are secured on shafts 248 and 249. The shafts 246 and 248 are journaled in the frames 114 and 115 and opposite ends of the shaft 249 are supported in vertical slots in said frames 114 and 115. The shaft 247 is mounted for slight vertical movement by means of a pair of slotted hangers 268 (Fig. 6) one of which is secured to the frame 114 and the other to the frame 115.

The feed and ejector rolls are driven in the following manner: Secured on the shaft 156 (Fig. 4) is a gear 250 operatively connected by a train of gears 251, 252, 253, 254 and 255 to a pinion 256 secured on one end of the ejector roll shaft 248. Secured on the other end of the shaft 248 is a pinion 257 (Fig. 5) meshing with an idler gear 258 which drives a gear 259 secured on the feed roll shaft 241. The gear 259 is connected by an intermediate gear 260 to a gear 261 secured on the feed roll shaft 240 and an idler pinion 262 connects the gear 261 to a gear 263 secured on the righthand end of the feed roll shaft 246. The gears 258 and 260 (Fig. 5) and the pinion 262 are rotatably supported by studs 264, 265 and 266 secured in the frame 114.

Attention is called to the fact that the gears 252 and 253 (Fig. 4) are secured together as also are the pinion 254 and the gear 255.

By referring to Fig. 4 it will be recalled that the main drive shaft 33 by means of the gear 155 and the intermediate gear 154 drives the gear 153 and the shaft 156 in a clockwise direction. This through the horizontal train of gears described above drives the pinion 256, the shaft 248 and the pinion 257 (Fig. 5) also in a clockwise direction. The pinion 257 by means of the train of gears shown in Fig. 5 drives the feed roll shafts 241 and 240 and 246 in a clockwise direction. The shaft 246 (Fig. 4) is geared to and drives the shaft 247 in a counterclockwise direction by means of a pair of gears 267.

The upper feed roll 233 (Fig. 6) is pressed into engagement with the lower feed roll 232 by means of a pair of compression springs 269 located at opposite ends of the shaft 247. The pressure between the rolls 232 and 233 may be varied by means of set screws 290 cooperating with the springs 269. The upper pressure rollers 235 and

237 (Fig. 4) are urged into engagement with the feed rolls 234 and 236 by means of springs 270, the upper ends of which are attached to the arms 242 and 243. The ejector pressure roll 239 (Figs. 4 and 6) is maintained in contact with the lower ejector feed roll 238 by means of a pair of hooks 271 which are hooked over opposite ends of the shaft 249 and urged downwardly by means of springs 272.

To repeat in part a statement made earlier herein, near the beginning of machine operations the slide 203 (Figs. 4 and 6) advances the bottom card in the reservoir or supply compartment 198 to the feed rolls 232 and 233 which feed the card between the plates 132 and 133 and into engagement with the feed rolls 234 and 235. These rolls carry the card onward into engagement with the rolls 236 and 237 which in cooperation with said rolls 234 and 235 moves the rearwardly disposed edge of the card into engagement with a pair of locating bars 273 the upper ends of which have previously been moved upward to obstruct the opening between the plates 132 and 133. This alines the record card longitudinally with the perforating punches 123 and immediately thereafter the slidable frame 134 starts its upward travel which disengages the rolls 235 and 237 from the feed rolls 234 and 236 said rolls 235 and 237 continuing to exert downward pressure on the record card to hold it in place during perforation thereof. Upon return movement downwardly of the frame 134 the bottom surface of the record card is brought into contact with the feed rolls 234 and 236 and as the locating bars 273 no longer obstruct the opening between the plates 132 and 133 the card is advanced to the ejector rolls 238 and 239 which pick the card up and deposit it in a receiving well 287. A plate 288 deflects the ejected cards downwardly to cause them to stack properly in the receiving well.

Directing attention to Figs. 4 and 8 secured on the shaft 151 is a plate cam 274 the periphery of which is arranged to cooperate with a roller 275 carried by a pitman 276 the rearward end of which is shaped to fit an annular groove in a hub 277 of the cam 274. The forward end of the pitman 276 is pivoted to an arm 278 of a yoke 279 rotatably supported by the shaft 147. The lower ends of the record card locating bars 273 are pivoted respectively to arms 280 and 281 of the yoke 279. The bars 273 extend upwardly through recesses in the bar 135 (see also Fig. 6) and into recesses in the die plate 133. A spring 282 tensioned between the yoke 279 and the pitman 276 urges said yoke counterclockwise and the pitman forwardly to maintain the roller 275 in contact with the periphery of the cam 274.

Soon after the machine starts to operate, the cam 274, in cooperation with the roller 275, moves the pitman 276 rearwardly to rock the yoke 279 clockwise. This moves the locating bars 273 upwardly causing the upper ends thereof to pass through the opening between the plates 132 and 133 and into apertures in the plate 132. Immediately after the card is perforated and prior to its ejection the cam 274 in cooperation with the spring 282 returns the pitman 276 and the yoke 279 to their home positions as shown in Fig. 4 to remove the obstructing upper end of the bar 273 from the opening between the plates 132 and 133. Immediately after this the record card is ejected as explained herein before.

Removably supported by a cross member of the cabinet base 120 (Fig. 6) is a receptacle 289 located directly below the perforating die plate 133.

This receptacle provides a convenient means of disposing of the punchings from the record cards.

It is thought unnecessary to enter into a lengthy explanation of machine operation as an understanding of the manner in which the instant machine is used may be obtained by perusing the foregoing description. It probably however will not be amiss to again state that the ledger or record card illustrated in Fig. 10 is the result of an adding operation, while the card depicted in Fig. 11 is the result of a resetting operation.

While the forms of mechanisms herein shown and described are admirably adapted to fulfill the objects primarily stated, it is to be understood that it is not intended to confine the invention to the forms of embodiment herein disclosed, for it is susceptible of embodiment in various forms all coming within the scope of the claims which follow.

I claim:

1. In a cash register capable of one and two-cycle operations, the combination of a card supply compartment; a constantly operated feeding mechanism for record cards; means arranged to make one excursion each machine operation to remove a record card from the supply compartment and present it to the feeding mechanism; constantly operated driving means for the re-moving and presenting means; and means to disengage the removing and presenting means from the driving means during the first cycle of a two-cycle machine operation and to re-engage the removing and presenting means with the driving means during the second cycle of a two-cycle machine operation.

2. In a cash register capable of one and two-cycle operations, the combination of a supply compartment for record cards; means to feed record cards; picker means to remove the record cards from the supply compartment and present them to the feeding means; means to drive the picker means; means connecting the driving means to the picker means; and means to give the connecting means one increment of movement to disconnect the driving means from the picker means during the first cycle of a two-cycle operation, said means also adapted to give the connecting means another increment of movement to reconnect the driving means to the picker means in the second cycle of a two-cycle machine operation.

3. In a machine of the class described, capable of different types of operation, the combination of a supply compartment for record cards; means to feed record cards; means to remove record cards from the supply compartment and present them to the feeding means; driving means for the removing and presenting means; means to connect the driving means to the removing and presenting means; manual means to give the connecting means one increment of movement during certain machine operations to disconnect the driving means from the removing and presenting means; and automatic means operable during said certain machine operations to give the connecting means another increment of movement to reconnect the driving means to the removing and presenting means.

4. In a cash register adapted to operate through one cycle of movement in adding operations and through two cycles of movement in total taking operations, the combination of a control lever to condition the machine for adding and total taking operations; cycle control means to cause

the machine to operate through two cycles when the control lever is moved away from adding position; a supply compartment for the record cards; means to feed record cards; means to remove the record cards from the supply compartment and advance them to the feeding means; driving means for the removing and advancing means; an element connecting the driving means to the removing and advancing means; means operated by the control lever when moved away from adding position to impart one increment of movement to the element to disconnect the removing and advancing means from the driving means, said last-named means adapted to be operated by the cycle control means to give another increment of movement to the element to reconnect the removing and advancing means to the driving means.

5. In a machine of the class described, the combination of means to feed record cards; means to advance the record cards to the feeding means; driving mechanism for the advancing means; a shiftable element normally connecting the driving means and the advancing means; means to shift the element a slight distance to disconnect the driving means from the advancing means, and means to actuate the last-named means to impart additional shifting movement to the element to reconnect the driving means to the advancing means.

6. In a machine of the class described having a cycle control mechanism to cause the machine to perform one or two cycle operations and a control member to set the cycle control mechanism to selectively cause the machine to operate through one or two cycles, the combination of a supply magazine for record cards, means to feed record cards, a card picker for removing a card from the magazine and advancing it to the feeding means, means to drive the card picker, an element connecting the picker with the driving means, means controlled by control member when set for two cycle operations to disconnect the element from the driving means, and means controlled by the cycle control mechanism to cause the last mentioned means to connect the element to the driving means in the second cycle of operation.

7. In a machine of the class described having a cycle control mechanism to cause the machine to operate through one cycle in adding operations and to operate through two cycles in total taking operations, a manually operable member to set the cycle control mechanism to selectively cause the machine to perform adding or total taking operations, and a recording mechanism actuated during each cycle of operation of the machine, the combination of a card supply magazine, means to transfer record cards from the supply magazine to the recording mechanism, means controlled by the member when moved to cause total taking operations to disable the transferring means to thereby render the recording mechanism ineffective, and means whereby the cycle control mechanism operates the last named means to enable the transferring means during the second cycle of operation of the machine, whereby the recording means can make records on the card during said second cycle of operation of the machine.

8. In a machine of the class described having a cycle control mechanism to cause the machine to perform one or two cycle operations, a manipulative member to condition the cycle control mechanism to selectively cause one or two cycle

- operations, means to make a record on a card, and means to feed the record cards to the recording means, the combination of means to remove cards from a supply compartment and advance them to the feeding means, means controlled by said manipulative member when moved to condition the cycle control mechanism for a two cycle operation to render the card removing and advancing means ineffective to prevent feeding of a card to the recording means during the first cycle, and means whereby the cycle control mechanism controls the last named means to render the removing and advancing means effective to cause a card to be presented to the feeding means in the second cycle of operation.
9. In a machine of the class described, having means to make records on record cards, and means to feed the cards to the recording means, said recording means and feeding means being operable during every cycle of movement of the machine, the combination of a manipulative device to condition the machine for one- or two-cycle operations, picker means operable to make one excursion during each machine operation to remove a record card from a supply compartment and to present said record card to the feeding means, drive means for the picker means, said driving means being operable through one or two cycles of movement depending on the type of machine operation, means normally connecting the picker means to the driving means during one-cycle operations of said machine, means actuated by the manipulative device to disengage the connecting means from the driving means during the first cycle of a two-cycle machine operation, and means to actuate the last-named means to reengage the connecting means with the driving means during the second cycle of a two-cycle operation.
10. In a machine of the class described arranged to perform single and plural cycle operations having a manually settable mechanism to selectively condition the machine for single or plural cycle operations, a supply magazine for record cards, means for making records on said cards, and feeding means for feeding cards to the recording means, said feeding means and recording means being operable during each cycle of operation of the machine, the combination of means for removing cards from said magazine and presenting them to the feeding means, and means controlled by the manually settable conditioning means when set for a plural cycle operation for disabling said removing and presenting means during the first cycle of a plural cycle operation to prevent a record from being made during this cycle of operation, said last mentioned means being automatically operated to render said removing and presenting means effective at the end of the first cycle of the plural cycle operation to enable the recording means to make a record on the card subsequent to this cycle of operation.
11. In a machine of the class described capable of performing single and plural cycle operations, having a manually settable means to selectively condition the machine for single or plural cycle operations, a supply magazine for record cards, recording mechanism, and means to feed record cards to the recording mechanism, said recording mechanism and feeding means being actuated during each cycle of operation of the machine, the combination of a card picker for removing a card from the supply magazine and presenting it to the card feeding means, driving means for said card picker, and coupling means controlled by said conditioning means when set for a plural cycle operation for disconnecting the picker from the driving means during the first cycle of a plural cycle operation, said coupling means being further automatically operated to connect said picker to the driving means for operation thereby during the second cycle of the plural cycle operation.
12. In a cash register operable to perform one or two cycle operations, having recording mechanism for recording data on record cards; a supply compartment for record cards; and constantly driven feed rollers for feeding record cards to the recording means; the combination of a reciprocable picker mechanism for removing cards from the supply compartment and advancing them to the feed rollers; drive means for said picker mechanism; means to couple said picker mechanism to its drive means for positive reciprocation thereby; means operable to selectively condition the cash register for one or two cycle operations, said conditioning means moving the coupling means to disconnect the picker from its driving means before a two cycle operation begins; and means operable during the two cycle operation to automatically move the coupling means to connect the picker mechanism to its drive during the second cycle of the two cycle operation whereby the recording means is rendered ineffective during the first cycle and effective during the second cycle of a two cycle operation.
13. In a cash register operable through one and two cycle machine operations and having means to initiate cyclic operation of the machine; movable means to selectively condition the machine for one or two cycles of operation; recording mechanism for recording data on record cards, said recording mechanism being operable in each machine cycle; a supply magazine for record cards; and constantly operating means to feed record cards to the recording mechanism; the combination of picker means to withdraw cards from the supply magazine and to deliver them to the feeding means; operating means for the picker means; means to connect the picker means to its operating means; said conditioning means when moved to control a two cycle operation being operable to move the connecting means to disconnect the picker from its drive before the initiating means has started a cyclic operation of the machine, to thereby render the recording means ineffective during the first cycle; and means for moving the connecting means during the cyclic operation of the machine whereby the picker is connected to its drive during the second cycle so that a card is fed to the recording means to render it effective during this cycle.
14. In a cash register operable to perform one- or two-cycle operations, the combination of a supply compartment for record cards; constantly driven feed rollers for feeding record cards; a reciprocable picker mechanism for removing cards from the supply compartment; drive means for said picker mechanism; means to couple said picker mechanism to its drive means for positive reciprocation thereby; means operable to selectively condition the cash register for one- or two-cycle operations, said conditioning means moving the coupling means to disconnect the picker from its driving means before a two-cycle operation begins; and means operable during the two-cycle operation to automatically move the coupling means to connect the picker mechanism to

its drive during the second cycle of the two-cycle operation whereby the recording means is rendered ineffective during the first cycle and effective during the second cycle of a two-cycle operation.

5. 15. In a cash register operable through one- and two-cycle machine operations and having means to initiate cyclic operation of the machine, the combination of movable means to selectively condition the machine for one or two cycles of operation; a supply magazine for record cards; picker means to withdraw cards from the supply magazine; operating means for the picker means; means to connect the picker means to its operating means; said conditioning means when moved to control a two-cycle operation being operable to move the connecting means to disconnect the picker from its drive before the initiating means has started a cyclic operation of the machine, 10 to thereby render the picker means ineffective during the first cycle; and means for moving the connecting means during the cyclic operation of the machine whereby the picker is connected to its drive during the second cycle so that a 15 card is fed from the supply magazine during this cycle.

16. In a machine of the class described which is operable to perform several types of machine operations, said machine including recording mechanism to make records on cards, the combination of means to feed record cards to the recording mechanism; means to advance the record cards to the feeding means; a manipulative device to condition the machine for one of 20 said several types of machine operations; means 25

operated by the manipulative device to disable the advancing means during a part of said one of the several types of machine operations; and automatic means to enable the advancing means during another part of said one of the several types of machine operations.

17. In a machine of the class described capable of operating through one or two cycles of movement, said machine including recording mechanism to make records on record material, the combination of means to feed the record material to the recording mechanism; means to advance the record material to the feeding means; means to positively reciprocate the advancing means, said reciprocating means normally coupled to the advancing means; and means to uncouple the advancing means from its reciprocating means during the first cycle of a two-cycle operation.

18. In a machine of the class described adapted to perform one- or two-cycle operations and including recording mechanism to make records on record material, the combination of means operable during every cycle of operation of the machine for feeding the record material to the recording means; means to advance the record material to the feeding means; and manually operable means to condition the machine for a two-cycle operation and to simultaneously disable the advancing means during the first cycle 20 of a two-cycle operation to thereby prevent feeding of record material to the recording means 25 during the first cycle of a two-cycle operation.
